ORNAMENTING TOOL

Ralph Barone, Newark, N. J.

Application March 1, 1933. Serial No. 659,161

5 Claims. (Cl. 41—5.5)

This invention relates to new and useful improvements in ornamenting devices, and particularly to devices which are manipulated on painted surfaces, while the paint is still wet, 5 whereby to form ornamental designs thereon.

One object of the invention is to provide a simple and inexpensive device which can be easily manipulated on a painted surface, to form various designs, and which is capable of adjustment to produce variations in the designs.

Other objects and advantages will be apparent from the following description when taken in connection with the accompanying drawing.

In the drawing:

15 Figure 1 is a top plan view of the tool.

Figure 2 is a bottom plan view of the same.

Figure 3 is a side elevation of the same.

Figure 4 is a transverse sectional view on the line 4—4 of Figure 1.

20 Figure 5 is a fragmentary sectional view, similar to Figure 4, showing two sleeves on a finger, and the washer associated with the star-shaped member.

Figure 6 is a perspective view of one of the 25 rubber sleeves.

Referring particularly to the accompanying drawing, 10 represents a block which may be of any desired thickness and contour, the contour of the one illustrated being octagonal. Carried 30 by each of the edge faces of the block, and extending therefrom at a right angle to the plane of said face, is a cylindrical stem or finger 12, a portion of the curved face of the finger being arranged in the plane of the lower face of the block, as clearly seen in the sectional views, 35 Figures 4 and 5.

Removably engaged on each of the fingers 12 is a length of rubber tubing 13, the outer face of which is shown as being longitudinally ribbed, 40 as at 14, and the outer end of which tube is cut off obliquely, so that the pointed end thereof projects beyond the outer end of the finger, as shown at 15. While I have shown these rubber tubes, which are, in effect sleeves, as being externally ribbed, it is to be understood that their 45 outer faces may be smooth, or may have any other desired designs molded thereon. The sleeves 13, being formed from soft rubber, the projecting points 15 will be flexible.

50 Should it be desired to produce a design of a different size, I slip onto each of the rubber sleeves 13, a rubber sleeve 16, of slightly greater diameter than the sleeve 13, said sleeve 16 being also obliquely cut, on its outer end, as at 17, 55 to form the flexible point 16', which may be

arranged to lie inwardly of the point of the sleeve 13, or outwardly therebeyond, as desired.

If it is desired to change the design, that is the pattern thereof, I substitute for the pointed tubes 13, tubes which have their outer ends cut off at right angles, these latter tubes being engaged directly on the fingers, or if larger ones are used, they are engaged on the smaller tubes which engage on the fingers.

Secured to the lower face of the block 10, and centrally thereof, is a flat piece of soft rubber or other suitable material 18, the same being shown as having the outline of an eight-pointed star. This may be varied, in contour, to effect differences in the designs on the surface being treated.

When the larger sleeves 16 are used, it is necessary to elevate the star-shaped member 18, from the lower face of the block 10, so that its working face will lie in the plane of the lower portions of the surfaces of said sleeves. To accomplish this I place a washer 18', of any suitable material, between the member 18, and the face of the block, the washer and member 18 being secured to the face of the block by 80 means of the screw 19.

Secured to the block, and extending upwardly, in arching relation to the upper face of the block, is a handle 11, which is adapted to be grasped by the user, for manipulating the device.

It will, of course, be understood that the fingers may be of different diameters and lengths, and the block may be formed with more or less side faces than illustrated, which 90 would also affect the design.

In the operation of the device, the operator grasps the handle 11, and places the device against the surface which has been previously painted, and while the paint is still wet, and rotates the device on said surface, in either direction, or first in one direction, and then in the other direction, as desired, to produce various different design effects, in the wet paint. The designs may be further varied by partially rotating the device, and then moving the device in a straight line, or a curved line, over the painted surface, as will readily be understood.

Also, by so manipulating the device as to flex the pointed ends of the rubber sleeves, further variations of the design may be produced.

Thus the device may be manipulated in a multitude of ways, whereby to produce as many different designs.

The rubber sleeves may easily be removed,

when they have become worn, and replaced by new ones, as found necessary.

What is claimed is:

1. An ornamenting device comprising a block having a face for operation on a surface to be ornamented, and radiating members on the block each having a face in the plane of said block face.
2. An ornamenting device comprising a block, a handle on the block, a resilient surface engaging member on one face of the block, fingers on the block, and resilient sleeves on said fingers, said sleeves having their outer ends cut off obliquely to provide flexible points.
- 15 3. An ornamenting device comprising a block

having a face for operation on a surface to be ornamented, fingers radiating from the sides of the block each having a face in the plane of the said block face, and removable sleeves on said fingers.

- 5 4. An ornamenting device comprising a block having a surface engaging face, radiating fingers on the block, and removable resilient sleeves on said fingers.

5. An ornamenting device comprising a block having a surface engaging face, radiating fingers projecting from the sides of the block, and resilient sleeves on the fingers each having a projecting flexible portion.
